US0D1065345S

(12) **United States Design Patent** (10) Patent No.: **US D1,065,345 S**
(45) Date of Patent: ** Mar. 4, 2025

(54) **PIECE FOR A BOARD AND TABLE GAME**

(71) Applicant: **GW Development UK Limited**,
London (GB)

(72) Inventor: **Gavin Waxkirsh**, London (GB)

(73) Assignee: **GW Development UK Limited**,
London (GB)

(**) Term: **15 Years**

(21) Appl. No.: **35/518,662**

(22) Filed: **Jun. 1, 2023**

(80) **Hague Agreement Data**

Int. Filing Date: **Jun. 1, 2023**

Int. Reg. No.: **DM/232015**

Int. Reg. Date: **Jun. 1, 2023**

Int. Reg. Pub. Date: **Oct. 13, 2023**

(51) **LOC (15) Cl. 21-01**

(52) **U.S. Cl.**

USPC **D21/386**

(58) **Field of Classification Search**

USPC D21/392, 394, 396, 386
